UNITED STATES PATENT OFFICE.

ADOLPH KARPEN, OF CHICAGO, ILLINOIS.

DESIGN FOR A CHAIR.

No. 37,606.

Specification for Design.

Patented Oct. 31, 1905.

Application filed August 17, 1905. Serial No. 274,632. Term of patent 7 years.

To all whom it may concern:

Be it known that I, ADOLPH KARPEN, a citizen of the United States, residing at Chicago, in the county of Cook and State of Illinois, have invented a new, original, and ornamental Design for Chairs, of which the following is a specification, reference being had to the accompanying drawing, forming part thereof.

The figure is a perspective view showing my new design.

I claim—

The ornamental design for a chair, as shown.

ADOLPH KARPEN.
